UNITED STATES PATENT OFFICE

JOHN C. STILLMAN, OF APPLETON, WISCONSIN, ASSIGNOR OF TWO-FIFTHS TO L. M. BETTS, OF WASHINGTON, DISTRICT OF COLUMBIA

TRAIN HEATING SYSTEM

Application filed July 14, 1927. Serial No. 205,670.

This invention relates to train heating systems.

Objects of this invention are to provide a novel form of train heating system in which 5 exhaust steam is utilized for the heating agent, and in which means are provided for preventing the formation of pockets of water or air in any portion of the system, so that the system may be effectively used 10 upon a train of any desired length and will thoroughly heat all of the radiators throughout the entire train.

Further objects are to provide a novel train heating system which is economical 15 in operation, which saves the condensed steam and returns a portion of such condensate to the tender and also supplies each of the several coaches with hot water.

Further objects are to provide a system 20 for heating a train by means of the exhaust steam without creating any increase in back pressure at the discharge or exhaust portion of the engine, and to so organize or relate the different portions of the system that a 25 thoroughly reliable and highly practical method of heating the cars results.

An embodiment of the invention is shown in the accompanying drawings in which:

Figure 1 is a diagrammatic view of one 30 of the coaches showing the heating system and the hot water supply system in place;

Figure 2 is a plan view of a portion of the structure shown in Figure 1.

Referring more particularly to the drawings, a coach is generally indicated at 24, 35 having a steam pipe 25 therein which is connected up with the steam chest of a locomotive and 25 indicates a suction drain pipe, which is connected with suitable means for 40 draining the hot condensed water from the exhausting steam supply and a hot water pipe 27 is also provided.

The pipe 26 is arranged immediately beneath the pipe 25 as is apparent from an 45 examination of the drawing, and it is to be noted that these pipes are connected adjacent their ends by means of small bleed pipes 27'. In Figure 1, the pipe 27 has been omitted for the sake of clearness. It is to 50 be noted that the pipes 25 and 26 cross over

the pipe 27, as may be seen from Figure 2, so that the pipe 27 is always positioned inwardly of the pipe 25 on opposite ends of the coaches. This permits reversal of the coaches and brings the pipes 25 and 27 55 at the correct relative position, irrespective of the end of the coach employed. Each of the coaches is similar in construction and therefore a description of the heating system for one will be sufficient.

It will be seen that a riser 28 extends upwardly from the pipe 25 to a header 29. This header is connected by means of heating pipes 30 with a second header 31. From the header 31, a pipe 32 extends downwardly 60 below the car floor and, as may be seen from Figure 2, joins a header 33 on the opposite side of the coach. From the header 33, heating pipes 34 extend to a header 35. A pipe 36 extends from the header 35 downwardly through the floor of the coach to the pipe 26.

It is to be noted that the pipes at opposite ends of the coaches are provided with cut-off valves. For example, the pipe 25 75 is provided with valves 37, the pipe 26 with valves 38', and the pipe 27 with valves 39. These valves are closed at the rear end of the rearmost of the coaches.

It will be seen from the description thus far given that the pipe 26 constitutes a suction or return pipe for the water formed by the condensing steam, and that it keeps the supply pipe 25 for the exhaust steam 80 clear of water and air pockets.

It will be seen also that the hot water pipe 27 supplies hot water to each of the coaches. Preferably, the coaches are each provided with a tank 40 which is connected by means of pipes 41 with the hot water pipe 27. It is to be noted that the pipes 41 90 communicate with the tank 40 adjacent its upper end and that the uppermost portion of the tank is provided with a small bleed pipe 42 by means of which air may pass outwardly from the tank. The lower portion of the tank is connected to the fixtures in the coach by means of the pipe 43.

The steam passes through the radiators 100 30 and 34 and each individual radiator may

be controlled by means of the manually operable valve 58, as shown in Figures 1 and 2. The condensed steam passes into the pipe 26. This pipe 26 forms also a continuous chain or line throughout the train and leads to the suction end of a steam pump (not shown). Thus, this last portion of the system is under a partial vacuum and, consequently, water is sucked from the radiators and they are kept filled with clear steam. In addition to this, the small connecting pipes 27' cause the sucking of all water in the main pipe line 25 into the suction pipe 26 and consequently keep such main line clear of both water and air and prevent any pocketing thereof.

I claim:

In a railway coach, the combination of a steam supply pipe and a suction drain pipe extending from one end of the coach to the other and arranged in superposed relation, a plurality of steam headers arranged in substantially rectangular formation, means for connecting one of the headers with the steam supply pipe, means for connecting one of the other headers with the suction drain pipe, means connecting the remaining headers, a plurality of parallel pipes connecting the first mentioned header with one of said remaining headers, a plurality of pipes connecting the second header with the other of said remaining headers to provide circulation between all of said headers and the steam supply pipe, and a plurality of small bleed pipes extending downwardly from the steam supply pipe to the suction drain pipe whereby the supply pipe is kept constantly free from air pockets.

In testimony that I claim the foregoing I have hereunto set my hand at Appleton, in the county of Outagamie and State of Wisconsin.

JOHN C. STILLMAN.
